INVENTOR

Charles F. Redlich
by his atty. J. H. Hubbard,

UNITED STATES PATENT OFFICE.

CHARLES F. REDLICH, OF BROOKLYN, NEW YORK.

DESIGN FOR A POWDER-SPRINKLER.

SPECIFICATION forming part of Design No. 21,104, dated October 6, 1891.

Application filed July 24, 1891. Serial No. 400,656. Term of patent 7 years.

To all whom it may concern:

Be it known that I, CHARLES F. REDLICH, a citizen of the United States, residing at Brooklyn, in the county of Kings and State of New York, have invented and devised a new and original Design for Powder-Sprinklers, of which the following is a specification, reference being had to the accompanying drawing, which forms a part thereof, and which shows 10 in elevation a powder-sprinkler in accordance with my design.

The leading features of my design consist of the bulbous body portion when combined with a cover whose outline is made up of the 15 covers 3 4 5, the relatively-slender neck 6, and the acorn-shaped tip or head 7, surmounting said neck.

In the drawing, 1 is the body of the powder-sprinkler, of bulbous outline and provided

with the outwardly-extended base 2. The 20 cover at its lowermost portion 3 is slightly larger in diameter than the top of the body. From the point 3 the major curves 4 extend inward and then outward to form the flange 5, from whose upper side minor curved lines 25 6 extend still farther upward to the acorn-shaped top 7, which surmounts the cover.

I claim -

The design for powder-sprinklers and the like, substantially as herein shown and described.

In testimony whereof I affix my signature in presence of two witnesses.

CHARLES F. REDLICH.
